Inventor,
Julius Roever,
By his Attorney,
W. B. Hutchinson,

UNITED STATES PATENT OFFICE.

JULIUS ROEVER, OF NEW YORK, N. Y., ASSIGNOR TO MARY A. ROEVER, OF RICHMOND HILL, NEW YORK.

SPRING-BED COVER.

1,267,593.

Specification of Letters Patent. Patented May 28, 1918.

Application filed May 24, 1916. Serial No. 99,482.

To all whom it may concern:

Be it known that I, JULIUS ROEVER, a citizen of the United States, and a resident of the city of New York, county of Queens, and 5 State of New York, have invented a new and useful Improvement in Spring-Bed Covers, of which the following is a full, clear, and exact description.

My invention relates to improvements in 10 covers for spring beds, and the object of my invention is to produce a simple, inexpensive and attractive cover which can be conveniently applied to a spring bed whether the spring bed is a box spring or otherwise, and 15 which will give to any spring to which it is applicable the appearance of a box spring. My invention is also intended to produce a cover which can be easily applied, and which has resilient or elastic portions along its 20 sides or ends which cause it to draw snugly to the sides of the spring bed and so fit nicely, and at the same time permit it to adjust itself to any slight irregularities of the bed. Another object of my invention is 25 to produce a cover which can be laid out flat so that it can be washed easily and as easily ironed, and further to construct the cover so that all the fastenings, which are preferably buttons, will be concealed when the cover is 30 attached to the spring bed, thus giving it the appearance of being permanently secured to the bed.

Reference is to be had to the accompanying drawings forming a part of this specification, in which similar reference characters 35 indicate corresponding parts in all the views.

Figure 1 is a plan view of the blank of the cover when spread out straight.

40 Fig. 2 is a broken perspective of the cover when folded up ready for application to a spring bed.

Fig. 3 is a broken perspective view showing 45 one end of the cover with the main flap turned up and with the elastic section in place.

Fig. 4 is a detail of an elastic section which can be used on one of the sides, preferably one of the end sides of the cover.

50 Fig. 5 is a perspective view showing the main flap turned up, the corner flaps turned in, and the elastic section removed, and

55 Fig. 6 is a broken perspective view showing the application of the cover to a spring bed.

The cover is made of a main blank 10 adapted to fold downward at the four sides as shown by dotted lines 11 and 12, these lines coinciding with the upper periphery lines of a bed to which the cover may be applied. Near the ends the blank is cut inwardly as shown at 12^a to the lines 11, thus forming at the ends of the blank main flaps 13 adapted to turn downward over the ends of a spring bed, and corner flaps 14 adapted to fold inward beneath the flaps 13 as hereinafter described. The corner flaps 14 are provided with buttonholes 15 near the outer edges as shown clearly in Fig. 1, and the flaps 13 are provided with buttons 16 on their inner sides and near the outer edges as shown clearly in the second figure. A section 17 is adapted to lie along the inner sides of the cover ends, and this section has an elastic portion 18 preferably of elastic webbing. Near the ends the section 17 has buttons 19 on its outer side.

When the cover is to be adapted to a bed, the sides are turned down along the lines 12, the corner flaps 14 are turned inward as 80 shown in Fig. 3, and the sections 18 are placed inside the flaps 14, and the buttons 19 button through the buttonholes 15 which are at the extreme ends of the flaps 14. The flaps 13 are then turned down and the buttons 16 buttoned into the buttonholes 15 which lie along the lower edges of the flaps 14. The cover is then complete, the buttons or fastenings do not show, and it has the 85 appearance of a complete permanent cover. 90

The cover can be drawn over a bed as shown in Fig. 6, and in this case I preferably use a pad 20 beneath the top of the cover, while the elastic elements serve to draw the sides snugly around the spring bed. 95

It will be understood, of course, that while the buttons and buttonholes are a simple and preferred means of fastening the several flaps and the section 17 together, still other forms of fastenings can be substituted without affecting the invention. It will also be noticed that when the cover is taken apart it can be readily cleansed or washed, can be laid out flat and easily ironed, and again readily applied to the bed. It will also be 100 understood that the elastic elements 17 are referred to as at the ends of the cover, but this is simply for convenience in describing the structure, and it will be understood that these elements and the corresponding flaps 110

might be on any two opposed sides of a rectangular structure like this, but they are more conveniently placed at the ends.

I claim:—

- 5 1. A cover comprising a main blank having end and corner flaps and adapted to turn down at the sides, the corner flaps being adapted to turn beneath the end flaps, means for fastening the several flaps together, and 10 elastic means connecting the corner flaps.
- 10 2. A bed spring cover comprising a main blank having corner flaps and main flaps located between the corner flaps, an elastic element connecting the corner flaps when the 15 latter are turned in, and means for securing the main flaps to the corner flaps.
- 15 3. A bed cover comprising a main blank adapted to turn down at the sides to form the sides of the cover, corner flaps forming extensions of such sides, main flaps located 20 between the corner flaps, elastic elements detachably secured to the corner flaps, and fastening devices connecting the lower edges of the main flaps with the corresponding 25 edges of the corner flaps.
- 25 4. A bed cover comprising a main blank adapted to turn down at the sides so as to

cover the sides of a bed, corner flaps forming extensions of the sides, main flaps extending from the blank between the corner flaps, detachable sections connecting opposed corner flaps, and fastening devices on the inner sides of the main flaps adapted to connect with the corner flaps, whereby the corner flaps are concealed by the main flaps and the fastening devices are also concealed.

5. A spring bed cover shaped to fit over a spring bed and having smooth exterior side portions and elastic elements concealed within the outer side portions and serving to 40 draw the said side portions snug against the bed.

6. A bed spring cover comprising a main blank adapted to lie flat when unfolded and having corner construction adapting it to be 45 fitted around the corners and sides of a spring bed, and concealed elastic elements disposed in the side portions of the cover and connecting the corner portions thereof.

JULIUS ROEVER.
